MATHEMATICAL TOP

Filed Jan. 7, 1922

UNITED STATES PATENT OFFICE.

JAMES B. ROGERS, OF CHICAGO, ILLINOIS.

MATHEMATICAL TOP.

Application filed January 7, 1922. Serial No. 527,565.

To all whom it may concern:

Be it known that I, JAMES B. ROGERS, a citizen of the United States, residing at Chicago, in the county of Cook and State of Illinois, have invented new and useful Improvements in Mathematical Tops, of which the following is a full, clear, concise, and exact description, reference being had to the accompanying drawing, forming a part 10 of this specification.

My invention relates to mathematical tops, such as may be used for educational or amusement purposes.

One of the objects of my invention is to 15 provide a mathematical top which will arouse interest by presenting a new and different problem for solution each time the top is spun; a further object is to provide novel number indicating and novel operation indicating means.

A further object of my invention is to provide a mathematical top which will be durable and efficient in operation, simple in construction and cheap to manufacture.

25 Further objects will appear from the detailed description to follow and from the appended claims.

In the drawings in which an embodiment of my invention is shown—

30 Figure 1 is a plan view of a mathematical top;

Fig. 2 is a section substantially on the line 2—2 of Fig. 1; and

Fig. 3 is a perspective view of the operation indicating ring.

The top comprises a central spindle 10, and a hollow sheet metal body portion 11, provided with two concentric ball races 12 and 13, and an operation indicating ring 14, 40 rotatably mounted on the spindle 10, and provided with a number of retarding wings 15, which meet with air resistance as the top spins, and retard the ring 14, causing relative movement between the ring 14 and 45 the body portion of the top. Balls 16 and 17 are provided, one for each ball race, these balls being mounted to travel in their respective races as the top spins, the inertia of the balls and the spinning and wobbling 50 motion of the top causing a relative movement between the balls and the body of the top as the top spins.

The inner ball race 12 is provided with five (5) little pockets or depressions 18, 55 equally spaced about the ball race, the ball

16 dropping into one of these pockets when the top stops spinning.

The upper portion of the body 11 of the top is provided with five (5) small sight openings 19, one located above each of the 60 pockets 18, so that one can readily see which one of the pockets 18 the ball 16 finally drops into.

In a similar manner, the outer ball race 13 is provided with ten (10) little pockets 65 or depressions 20, the upper part of the hollow body of the top being provided with ten (10) small sight openings 21, one located above each of the pockets 20, so that one can readily see into which of the pockets 70 20 the ball 17 finally drops.

The hollow body 11 may be formed of upper and lower sheet metal members 22 and 23, the lower member having the ball races and pockets stamped therein, and the upper 75 member 22 forming a cover portion and having the sight openings 19 and 21 punched therein.

The stampings 22 and 23 forming the body portion of the top may be held on the spindle 80 10, which may be of metal, by means of the ears or lugs 24, which may be formed on the metal spindle 10, after the sheet metal members 22 and 23 are in place, by an operation well-known in the manufacture of 85 toys and the like.

In order to properly space the sheet metal members 22 and 23, and to insure proper clearance for the balls 16 and 17, a spacing collar 25 may be provided, surrounding the 90 spindle 10 and placed between the stampings 22 and 23, as shown in Fig. 2. The upper stamping 22 is positioned against a shoulder portion 26 on the spindle 10.

The ring 14 is rotatably mounted on the 95 enlarged portion 27 of the spindle, being held in place between the upper stamping 22 and an annular flange 28, formed on the spindle 10. In order to lessen the friction between the ring 14 and the body of the 100 top, an annular bead 29 may be formed on the ring so that there will be line contact between the ring and the upper stamping 22, thereby making it easy for the air resistance acting on the wings 15 to cause retardation of the ring 14 and relative motion between the ring and the body portion 105 of the top.

Both sets of sight openings may be numbered, the inner circle of sight openings be- 110

ing shown as numbered from 1 to 5 and the outer circle of sight openings being shown as numbered 1 to 10. The operation indicating ring 14 may be provided with a number of operation indicating signs, such as plus, minus, times, divided by and zero, the latter indicating that no operation is to be performed.

In using the device, the top is spun in the usual manner. As the top spins, the balls 16 and 17 move around in the ball races, and the operation indicating ring 14 is retarded by the air resistance and moved relative to the body portion of the top. When the top finally comes to rest, the ball 16 will drop into one of the pockets provided for it, the ball 17 will drop into one of the pockets provided for it, and the operation indicating means will come to rest.

20 The person spinning the top observes the number of the pocket in which the ball 16 rests, the number of the pocket in which the ball 17 has come to rest, and observes which one of the operation indicating signs on the 25 operation indicating ring has stopped nearest to the ball in the inner ball race. As shown in Fig. 1, the ball 16 has come to rest in the pocket 3, the ball 17 has come to rest in the pocket 6, and the indicating ring 30 14 has stopped with a minus sign nearest the ball 16. The problem is, therefore, 6 minus 3.

If the ball 16 should stop in the pocket 4, the ball 17 in the pocket 9, and the operation 35 indicating ring 14 to stop with the multiplication sign nearest the inner ball race, the problem presented would be 4 times 9.

If the operation indicating ring 14 comes to rest with the zero nearest the ball in the 40 inner ball race, no problem is presented, and one simply spins the top over again.

When the top is spinning, the balls 16 and 17 fly outwardly, the ball 17 flying clear out to about the point indicated at 30, and the 45 ball 16 flying clear out to about the point indicated at 31 in Fig. 2. Thus, the balls 16 are free to move without being interfered in their movement by the depressions or pockets 18 and 20.

50 The slope of the lower stamping 23 at the portions 32 and 33 in Fig. 1 is such that when the top comes to rest the balls 16 and 17 will roll inwardly, and fall into the pockets provided therefor.

55 The top may also be used in a somewhat different manner as follows: the top is spun in the usual manner, but before it comes to rest, the person spinning the top grasps it firmly, holding it in upright position, either 60 by grasping the handle 10, or the body portion of the top. When the top is suddenly arrested, the balls 16 and 17 continue to travel around in the ball races, for a number of revolutions, centrifugal force holding 65 them in the outer portion of their respective

ball races, so that they are not interfered with in their movement by the pockets 18 and 20.

The balls gradually slow up in their movement, however, and each finally rolls into one of the pockets. The annular bead at the point 31 serves to prevent the ball 16 from escaping outwardly beyond the confines of the inner ball race, and the flanges which meet at the point indicated at 30 serve to prevent the outer ball 17 from escaping beyond the confines of its circular ball race.

70 While I have shown but one embodiment of my invention, it is obvious that it may be embodied in other forms covered and defined by the appended claims.

Having thus described my invention, what I claim as new and desire to secure by Letters Patent of the United States is—

1. A top comprising a spinnable body provided with a circular ball race, and a ball mounted to travel in said race as the top spins and means for preventing the ball from escaping outwardly beyond the confines of said circular ball race.

2. A top comprising a spinnable body portion provided with a circular ball race concentric with said body, and a ball mounted to travel in said ball race as the top spins and means for preventing the ball from escaping outwardly beyond the confines of said circular ball race.

3. A top comprising a spinnable body provided with a pair of circular ball races concentric with respect to said body portion, and two balls, one for each ball race, mounted to travel in said races respectively as the top spins and means for preventing said balls from escaping outwardly beyond the confines of said circular ball races.

4. A top comprising a spinnable body provided with a circular ball race, and a ball mounted to travel in said ball race as the top spins, said ball race being provided with a series of pockets, into one of which said ball drops when the top stops spinning and means for preventing the ball from escaping outwardly beyond the confines of said circular ball race.

5. A top comprising a spinnable body, comprising upper and lower portions, said lower portion being provided with a ball race, a ball mounted to travel in said ball race as the top spins, said upper portion being provided with a series of sight openings through which said ball may be seen, said ball race being provided with a series of pockets, one located under each sight opening, whereby said ball will drop into one of said pockets and be visible through said sight opening when the top stops spinning.

6. A calculating top comprising a spinnable body, two changeable number indicating means, each mounted for independent

movement on said body, and changeable operation indicating means also movably mounted on said body, whereby said operation indicating means serves to indicate 5 various operations which may be performed with respect to said numbers, each of said changeable number indicating means comprising a ball race, and a ball mounted to travel in said race as said top spins, said operation indicating means comprising an annular member concentric with said body portion, and rotatably mounted thereon, and provided with retarding wings whereby as said top spins the resistance of the air will cause movement of said operation indicating 15 means.

In witness whereof, I have hereunto subscribed my name.

JAMES B. ROGERS.
